Fig. 3.

Fig. 4.

Efig. 5.

To all whom it may concern:

Be it known that we, Harry Rosenfeld, Victor Reiter, and Max Deakter, residing at Miami Beach, Miami, and Coral Gables, respectively, in the county of Dade and State of Florida, have invented a new, original, and ornamental Design for Lounge Chair, of which the following is a specification, reference being had to the accompanying drawings, forming a part hereof.

We claim:
The ornamental design for a lounge chair, substantially as shown.
